A. L. THURAS

ACOUSTICAL INSTRUMENT

Filed Dec. 20, 1924

Inventor:
Albert L. Thuras.

by *Edward A. Atty*

UNITED STATES PATENT OFFICE.

ALBERT L. THURAS, OF EAST ORANGE, NEW JERSEY, ASSIGNOR TO WESTERN ELECTRIC COMPANY, INCORPORATED, OF NEW YORK, N. Y., A CORPORATION OF NEW YORK.

ACOUSTICAL INSTRUMENT.

Application filed December 20, 1924. Serial No. 757,277.

To all whom it may concern:

Be it known that I, ALBERT L. THURAS, a citizen of the United States of America, residing at 75 Ampere Parkway, East Orange, in the county of Essex, State of New Jersey, have invented certain new and useful Improvements in Acoustical Instruments, of which the following is a full, clear, concise, and exact description.

10 This invention relates to acoustical instruments and has for an object an improved sound passage for instruments used in the reception or transmission of sound.

According to one form of this invention, 15 the sound passage comprises a stationary wall through which is an opening leading to a sound delivering means and a diaphragm movable toward and away from the stationary wall through the medium of suitable 20 means, such, for example, as the stylus of a phonograph or the electromagnet of a telephone receiver. The stationary wall of the sound box is so shaped relative to the diaphragm that the instantaneous vibrational 25 velocity of the air throughout the sound box is constant. With this form of chamber, frictional losses are reduced to a minimum and the maximum quality of sound reproduction is obtained.

30 Referring now to the drawings, Fig. 1 is a section through a phonograph sound box embodying the invention and Fig. 2 is a similar view of a modified form.

The sound box shown in Fig. 1 of the 35 drawings comprises an annular member 10 having a curved inner surface 11 together with a diaphragm 12 which is clamped to the edge of the member 10 in any suitable manner. The opening 13 through the member 10 leads to a suitable sound delivering 40 means (not shown). A stylus 14 is connected to the diaphragm through the medium of a rod 15 whereby oscillations of the stylus cause vibration of the diaphragm. 45 The surface 11 is so curved with respect to the diaphragm 12 that the instantaneous vibrational velocity of the air throughout the sound box is constant. This desired condition is found to prevail when the ratio 50 of the volume of air displaced by an annu-

lar element of the diaphragm 12 to the area of the opening through which the air is displaced is the same as the ratio of the total volume displaced by the diaphragm 12 to the area of the opening 13. Thus, considering the volume of air displaced by the annulus a_1 , the ratio between it and the area of the opening b_1 between the edge from the annulus and the face 11 will be the same as the ratio between the volume of air displaced by the annulus a_2 and the area of the opening b_2 between the edge of the annulus a_2 and the face 11, this ratio being equal to the ratio of the total volume of air displaced by the diaphragm 12 to the area of the opening 13.

55 The shape of the face 11 may be obtained as follows:

Let

$y_2 = f(x)$ = cross sectional shape of the diaphragm 12 deflected. 70

$y_1 = \Phi(x)$ = cross sectional shape of the face 11.

b = the radius of the opening 13.

a = the radius of the diaphragm 12. 75

Then for constant instantaneous vibrational velocity throughout the chamber

$$\Phi(x) = f(x) + \frac{b^2}{2x} \frac{\int x^a x f'(x) dx}{\int x^a x f(x) dx}. \quad (1)$$

80 In sound producers the term $f(x)$ of this equation is small or negligible compared to the term

$$\frac{b^2}{2x} \frac{\int x^a x f'(x) dx}{\int x^a x f(x) dx}. \quad (2)$$

85 Integrating this equation for various values of a determines the shape of the inner wall 11.

In Fig. 2, the diaphragm 12 is of the plunger type and consequently its amplitude of vibration (d) is constant. As a result the relationship necessary to produce constant instantaneous vibrational velocity of air throughout the sound box is simplified. In this instance, the desired condition is obtained where the ratio of the area of the annulus a_1 to the area of the opening b_1 , equals the ratio between the area of a_2 and area of the opening b_2 , and also equals the ratio of the ef- 90

fective area of the diaphragm to the area of the opening 13. In this instance, the equation

$$y_1 = d + \frac{b^2}{2x} \frac{\int_x^a xf(x)dx}{\int_0^a xf(x)dx} \quad (3)$$

becomes

$$y_1 = d + \frac{b^2}{2x} \frac{a^2 - x^2}{a^2} \quad (4)$$

10 which can be readily solved by substituting values of a .

What is claimed is:

1. In an acoustic apparatus, a sound chamber, and means for setting up sound vibrations in said chamber, said chamber being shaped to cause the instantaneous vibrational velocity of the air to be substantially constant throughout the chamber.
- 20 2. In an acoustic apparatus, a sound chamber, a diaphragm across said chamber for setting up sound vibrations therein, and a sound passage communicating with the sound chamber, the separation between the diaphragm and each point of the chamber wall leading to the sound passage being such that the vibrational velocity of the

30 sound waves from all portions of the diaphragm is substantially the same.

3. A sound box for acoustical instruments comprising a stationary wall having a delivery orifice and a diaphragm, the inner face of the stationary wall being so shaped that the ratio of the volume of air displaced by an annulus of the diaphragm to the area 35 of the opening through which the air is displaced equals the ratio of the total volume of air displaced by the diaphragm to the area of said delivery orifice.

4. A sound box for acoustical instruments 40 comprising a stationary wall having a delivery orifice and a diaphragm, the inner face of the stationary wall being so shaped that the ratio of the area of an annulus of the diaphragm to the area of the surface 45 between the edge of said annulus and inner face of said wall equals the ration between the area of the diaphragm and the area of the delivery orifice.

In witness whereof, I hereunto subscribe 50 my name this 20th day of December A. D., 1924.

ALBERT L. THURAS.
